(57) **CLAIM**

The ornamental design for a heat shield for firearm suppressors as shown and described.

DESCRIPTION

FIG. 1 is a back, bottom, and right side perspective view of a ventilating heat shield for firearm suppressors showing my new design.

FIG. 2 is a front, top and left side perspective view thereof.

FIG. 3 is a top view thereof, the bottom view being a mirror image thereof.

FIG. 4 is a right side view thereof, the left side being a mirror image thereof.

FIG. 5 is a front view thereof; and,

FIG. 6 is a back view thereof.
